UNITED STATES PATENT OFFICE.

JAMES A. MCGINLEY, OF SPRINGFIELD, MASSACHUSETTS.

OAR-LOCK.

SPECIFICATION forming part of Letters Patent No. 611,436, dated September 27, 1898.

Application filed February 14, 1898. Serial No. 670,168. (No model.)

To all whom it may concern:

Be it known that I, JAMES A. MCGINLEY, a citizen of the United States, and a resident of Springfield, in the county of Hampden and 5 State of Massachusetts, have invented certain new and useful Improvements in Oar-Locks, of which the following is a specification.

This invention relates to improvements in oar-locks, the objects of the invention being 10 to provide an oar-lock which is most simple, cheap, and practicable of construction, and which when placed in its socket is susceptible of all desired play or oscillation by being free to partially rotate as the oars have their 15 swinging movements, which is durable, without tendency to break out the woodwork at the rail of the boat in which the oar-lock is set, and which is of such a character that the oar-lock can never become detached accidentally to be lost overboard, although freedom of detachment, as purposed, constitutes 20 one of the important advantages incidental to the invention.

The invention comprises, in combination 25 with an oar-lock having a screw-threaded stem, an externally-threaded cylindrical socket-piece or bushing adapted to be set and screw-engaged in the woodwork at the side or rail of the boat and having an internal screw-threaded socket in which the said threaded stem of the oar-lock may engage, and specific 30 means for enabling the externally-threaded socket-piece to be sunk within the rail of the boat and to leave its upper end flush with the 35 top of the rail.

Reference is to be had to the accompanying drawings, in which my improvements in oar-locks are illustrated, and in which—

Figure 1 is a sectional elevation showing 40 the oar-lock as seated and screw-engaged in the specially-provided socket-bushing therefor, which latter is screw-engaged in a socket for the reception thereof provided in the side rail of the boat. Fig. 2 shows the bushing- 45 piece and boat-rail in perspective. Fig. 3 is a plan view of the bottom end of the bushing or socket-piece in Fig. 2.

In the drawings, A represents the oar-lock of the usual U shape, the same having the 50 stem a. The said stem a is provided with a comparatively coarse screw-thread.

B represents a socket piece or bushing, the same being both externally and internally screw-threaded, the internal screw-threads being for the reception and engagement there- 55 in of the screw-threaded stem of the oar-lock, while by the external screw-threads the said socket-piece has a screw engagement in a properly-bored hole therefor in the rail proper of the boat or in a block bolted to the rail. 60 The externally and internally threaded socket-bushing is shown as tubular and of even diameter from top to bottom, provided at its lower end with a web or wall d², having therein the slot d³, by means of which a screw-driver 65 or like implement entered through the top open end of the fitting may be employed in its engagement with said slot to turn the socket-bushing down to position in the hole therefor bored in the top of the rail to bring 70 the upper end of the fitting just flush with the level of the rail top.

It will be apparent on a glance at the drawings that this oar-lock may be readily unscrewed when it is desired to remove it; that 75 when in use the oar-lock is left about a half a rotation from seating—that is, the shoulder b at the base of the oar-lock yoke and where the stem joins this base is left just clear of the top of the socket-bushing—so that in the 80 action of the oars the oar-lock may have all required oscillation about a line coincident with the axis of its stem, the screw-thread engagement which the stem has with the socket-bushing permitting this oscillation 85 with the utmost freedom, and yet without any tendency of the oar-lock to shackle or wabble in its support; that the oar-lock could never become so far turned outwardly as to fall from its socket without being perceived; that 90 there is nothing expensive of construction or liable to derangement, and that the parts may be cheaply made and most easily applied.

I am of course aware that a socket-bushing has been in different situations set by screw-thread engagement within woodwork, and I 95 am also aware that the screw-threaded shanks of some various contrivances have been screw-threaded in socket-pieces, and I make no such broad claim as to conflict with these; but 100

What I do claim, and desire to secure by Letters Patent, is—

The combination with the rail of the boat having a hole bored therein, of the socket-
bushing B externally and also internally
screw-threaded and provided with the bottom
5 web d^2 having the slot d^3 , and screw-engaged
in said hole, and the oar-lock having the **U**-
shaped top with the base-shoulder b and the
screw-threaded stem screw-engaging in said

internally-threaded bushing, substantially as
described.

Signed by me, at Springfield, Massachusetts,
this 9th day of February, 1898.

JAMES A. MCGINLEY.
